UNITED STATES PATENT OFFICE

2,676,051

LATCH SPINDLE CONSTRUCTION

Carl A. Hillgren, Huntington Park, Calif.

Application November 7, 1950, Serial No. 194,528

5 Claims. (Cl. 292—358)

1

The application relates to door hardware and has particular reference to a latch set of the type customarily referred to as cylindrical latch sets wherein the operating parts are confined to a small space almost entirely encompassed by the knobs together with a transverse aperture of small cross-sectional area designed to accommodate a particularly compact latch mechanism. The application is a continuation-in-part of co-pending application Serial No. 92,107, filed May 9, 1949, now Patent No. 2,662,238, issued December 15, 1953.

In the assembly and installation of lock sets or latch sets, however they may be designated in the trade, the competitive character of the business has made increasing demands upon simplification of the structure both from the point of economy of manufacture and such economies as may be effected in the installation. The usual factors necessitating such improvements have been amplified to a great extent by the materially increasing cost of wages for skilled artisans and mechanics. Moreover, when articles of this general character are produced on production line methods, assembly operations must be minimized to as great an extent as possible, the number of parts need be reduced, especially those parts requiring assembly by hand, and the assembly operation must be simplified to the end that it can be quickly performed by persons relatively less skilled than previously in handling the assembly of such mechanisms.

Also from the point of view of installation it has been found that in the case of lock sets or latch sets which have been constructed with a great degree of precision, they must of necessity be installed with a corresponding amount of precision in the wooden door frame to assure their successful operation. Lack of precision in a great many instances has meant inefficient operation of the hardware item because of friction or binding of the parts when the movable parts have been forced into out-of-line openings bored into the door material.

With a view to overcoming the defects previously experienced it is among the objects of the invention to provide a new and improved latch set which is especially economical to manufacture and assemble and which at the same time is particularly easy to install.

Another object of the invention is to provide a new and improved latch set which can be readily accommodated to doors of different thickness without requiring any change in the standard design or dimension.

2

Still another object of the invention is to provide a new and improved latch set of a type permitting either handle to be turned independently of the other and without the necessity of having the handle turn which is not grasped manually, thereby taking advantage of a separable spindle between the handles adjustable in an axial direction so that the effective length of the spindle can be varied and to so construct the latch set to the end that each part in turn may be suitably anchored to the door without it being necessary for the mechanic to temporarily hold any one part in place until a succeeding part is attached in position.

Among still other objects of the invention is to provide a new and improved latch set of the type described herein wherein when the spindle is separable the separate parts will work with complete satisfaction even though holes adapted to receive them are not made in precise alignment.

It is also an object to provide both parts of the separable spindle of a construction such that they may operate satisfactorily and without binding under conditions wherein the aperture for the latch housing is not in precise alignment or wherein it may be located nearer either side of the door, depending upon conditions of installation, without requiring any special adjustment of the parts of the device.

With these and other objects in view, the invention consists in the construction, arrangement and combination of the various parts of the device whereby the objects contemplated are attained, as hereinafter set forth, pointed out in the appended claims and illustrated in the accompanying drawings.

In the drawings:

Figure 1 is a plan view of the latch set in position in a door wherein the door is shown in section.

Figure 2 is a partial cross-sectional view taken on the line 2—2 of Figure 1.

Figure 3 is an exploded view in perspective showing the different parts as they appear prior to assembly in order that the mechanism may be clearly understood.

Figure 4 is a perspective view of what may be termed a sub-assembly of one part of the separable spindle.

Figure 5 is a plan view showing the spindle housing and appended knobs partially in section and showing the location of the adjacent end of the latch housing.

Figure 6 is a longitudinal sectional view of the removable knob and adjacent spindle part.

Figure 7 is a plan view of the parts applied to a door of greater thickness than that illustrated in Figure 1.

Figure 8 is a view similar to Figure 1 showing to a slightly exaggerated degree the position of the parts for successful manipulation wherein holes in the door adapted to receive them have been made slightly out of alignment.

The features described in connection with this continuation-in-part application have been set forth in company with a latch set provided with a cylindrical lock and a privacy lock in Patent No. 2,662,388 and are here simplified in a simple latch for clarity.

In order to accomplish the objects set forth the structure herein described has been made in a manner such that a housing 10 is provided which may appropriately be termed a spindle housing constructed in such a manner that it completely encompasses the moving parts of the spindle with a rugged housing to the end that even though the housing may be jammed in a hole bored in the door not in precise alignment, operation of the spindle will not be impaired by binding or friction. Also a latch housing 11 is made in a similar manner in that the housing is rugged permitting all of the parts within it, which may be of one or another conventional design as desired, to operate properly even though the latch housing may also be slightly out of line. The junction of the latch housing with the spindle housing is made somewhat free and loose fitting as well as adjustable so that even though the hole for the latch housing is nearer one surface or another of the door than it should be, the latch housing connection with the spindle housing readily adjusts itself to the change in either direction. By making the spindle separable, either or both parts may be slightly out of alignment but because of the somewhat looseness of the fit between them and the character of the cooperation between the spindle and moving portions within the latch housing, all parts continue to function properly.

Specifically the parts of the latch set are designed for incorporation in a door 12 which has an aperture 13 designed to receive the spindle housing. Because the aperture is of large diameter and because of a frequent need for keeping a clean-cut hole on both sides of the door, it is frequently advisable to bore the hole forming the aperture 13 partly inwardly from one side of the door and partly inwardly from the opposite side of the door. An aperture 14 for the latch housing is bored inwardly from the edge of the door so that it joins with and communicates with the aperture 13. The location of the strike plate in the door jamb may determine to some extent the location of the aperture 14 as being more nearly adjacent one side of the door than the other. Because of circumstances accompanying the fitting of the latch set to the door or lack of skill of the workman, any one or all of the apertures may be slightly out of alignment when made.

The latch set described herein comprises in addition to the spindle housing a separable spindle having one part 15 cooperating with another part 16. The part 15 as best illustrated in Figures 3 and 5 includes a square end 17 adapted to have a pressed fit in a correspondingly apertured plug 18 which is a part of a handle 19. The plug 18 has a shoulder 20 adapted to bear against the outer surface of an escutcheon plate 21 which forms a part of the

spindle housing. The spindle part 15 also has a shoulder 22 adapted to bear against the opposite side of the escutcheon plate so that the spindle part is held in position with respect to the escutcheon plate in which position it is adapted to freely rotate. A decorative shell 23 may be applied over the exterior of the escutcheon plate. It should also be noted that a lug 24 may be made a part of the escutcheon plate or the spindle housing in order to locate it in the aperture 13.

On the opposite side of the door is positioned the spindle part 16 which is separately mounted in an escutcheon plate 30. The spindle part 16 has a semi-cylindrical element 31 which is adapted to lie within a somewhat larger semi-cylindrical element 32 on the spindle part 15 and coaxial therewith.

To facilitate mounting of the spindle part 16, this part is made up of two separate pieces, the assembly of which can best be seen in Figure 6. As there shown the outer portion of the spindle part 16 is made of a core 33 enjoining a ring portion 34 presenting a shoulder to the escutcheon plate 30. On the opposite side of the escutcheon plate from the ring portion 34 there is positioned a sleeve 35 which is designed to fit over the core 33 with a sliding fit. In the core 33 is a detent 36 pressed outwardly by a spring 37, the detent having thereon a shoulder 38. To assemble the core and the sleeve the detent is depressed and the sleeve applied over the core until the detent springs outwardly into a hole 39 in the sleeve to a position wherein the outer end of the detent protrudes for some distance beyond the exterior surface of the sleeve. The shoulder 38 limits movement of the detent outwardly. In this manner the spindle part 16 is rotatably secured in the escutcheon plate 30.

Before the separable spindle is fixed in the door the latch housing 11 is inserted in place. As shown in Figures 1 and 3 the latch housing 11 includes a latch element or bolt 45 which extends outwardly to engage a conventional strike plate in the door frame. A plate 46 is mounted on the latch housing 11 and screw holes 47 are provided for the insertion of screws through the plate 46 to secure it in the door. An actuator element 48 extends from the opposite end of the latch housing as the latch 45 and mechanism of a conventional character, not shown, may be provided in the latch housing to cause the latch to be withdrawn when the actuator element is driven into the latch housing. The latch mechanism is of a reciprocating type wherein when the actuator is moved outwardly toward the bolt 45 the bolt is retracted. Rotation of either the semi-cylindrical element 32 of the spindle 15 or the part 31 of the spindle 16 causes one edge or the other to press against the actuator element 48 depending on which way the knobs are rotated. Suitable latch mechanism is illustrated in Patent No. 2,662,388.

In order that the latch housing may be attached to the spindle housing, the latch housing is provided with oppositely disposed transverse recesses 50 shown to good advantage in Figure 2. These recesses are designed to receive inturned edges 51 of the spindle housing 10, the inturned edges defining the sides of an open end slot 52 in the spindle housing. In order to accomplish the objects of the invention the transverse recesses are made sufficiently large to have a rather loose fit with respect to the in-

turned edges to permit a certain freedom of movement and adjustment therebetween.

When the latch set is placed in the hands of the mechanic who is to install it in a door, the handle 19, spindle part 15, and spindle housing 10 are permanently attached together in what may be described as a sub-assembly, the spindle part being so positioned that it rotates freely within the spindle housing. The spindle part 16 is also initially assembled so as to be rotatably mounted in the escutcheon plate 30. The latch housing 11 is assembled complete as illustrated in Figure 3.

Assuming that the apertures 13 and 14 are cut into the door, the usual practice is first to insert the latch housing into the aperture 14 and to secure the latch housing therein by wood screws applied through the holes 41 in the plate 46 to the edge of the door. Then the spindle housing 10 is thrust into the aperture 30 from one side so that the slot 52 encompasses the inside end of the latch housing in a position wherein inturned edges 51 slide into the recesses 50 of the spindle housing. Next the part 16 and attached escutcheon plate 30 is inserted into the aperture 13 from the opposite side of the door so that the semi-cylindrical parts 31 and 32 occupy positions overlying each other as depicted in Figures 1, 2 and 5. It should be noted at this point that the door can be virtually of any thickness within the limits of length of the semi-cylindrical parts so long as the door is not so thick as to prevent some portion of the semi-cylindrical parts from lying beneath the actuator element 48 which extends beyond the inside end of the latch housing. The decorative plate 40 is then applied over the exterior of the escutcheon plate 30 and bolts or screws, not shown, are applied through the aperture 41 in the decorative plate and 42 in the escutcheon plate and then threadedly engaged in holes 43 in the spindle housing. The bolts or screws are tightened in place and the latch set is mounted in the door except for the application of a removable handle 53. With regard to the handle 53 it should be noted that in addition to being applied last, it is provided with a detent aperture 54 at one side of a flange 55 and that the flange 55 is adapted to fit snugly around the outside end of the sleeve 35. The same detent 36 which is spring pressed to engage the core 33 with the sleeve 35 also serves to engage itself in the detent aperture 54, thereby to retain the handle 53 non-rotatably fixed to the outside end of the spindle part 16.

By following the construction herein described and the application of the parts to a door as herein noted, it will become apparent that the entire assembly operation requires only two bolts or screws to hold all of the parts together except that wood screws may in addition be used to hold the latch housing in place.

To illustrate adaptability of the separable spindle to accommodate doors of different thickness attention is directed to Figure 7 showing a door 12' greater in thickness than the door 12 by a distance A. Precisely the same latch set parts fit the door 12', the only difference in assembled position being that the spindle parts do not overlap each other for quite the same distance as illustrated in Figure 5. The door may even be still wider without the parts becoming so far separated as to be unworkable. Any thickness at all between maximum and minimum dimensions can be accommodated by the latch set.

As illustrated in Figure 8 occasions may arise where the mechanic in drilling the aperture 13 may not have the axes of the apertures in precise alignment on both sides of the door. It might also be that the surfaces of the door under some circumstances are not precisely parallel. Other conditions might occur to force the axis 60 of the spindle part 15 out of alignment with the axis 61 of the spindle part 16. The misalignment is illustrated in slightly exaggerated form in Figure 8 to show how the parts operate successfully regardless of this misalignment. Under those circumstances the semi-cylindrical parts 31 and 32, being of such a loose fit relative to each other, may be mounted cocked at an angle one from the other but there will be no binding between the parts sufficient to restrict rotation of either handle because of the looseness of fit of the parts. At the same time rotation of either handle causing rotation of either semi-cylindrical part is sufficient to depress the actuator element 48 moving it in a direction to release the latch 45. The latch can be released just as long as any portion of the semi-cylindrical elements lie beneath the actuator.

Still other occasions may arise where the axis 62 of the aperture 14 is not in true perpendicular alignment with either or both of the axes 60 or 61. Should this occasion arise even to the extent suggested by way of example in Figure 8, the latch will still be capable of successful operation by both handles. What accomplishes this is the loose fit of the inwardly extending edges 51 within the recesses 50, thereby permitting some deviation from a perfect alignment between the latch housing and the axis of the spindle. Under the circumstances last defined even if there should be some binding between the exterior of the latch housing 11 and any part of the door itself, it will not affect operation of the mechanical parts inside the housing since they are entirely free from binding. This remains true even though there may be a binding action between the inwardly turned edges 51 and the recesses 50. Whether or not the axis of the latch housing is out of alignment with either or both of the axes of the spindle parts has no detrimental effect on manipulation of the latch by both handles.

Further still, in the event of a changed thickness of the door, for example, the axis 62 may be shifted nearer one side of the door than the other and may or may not be in precise perpendicular relationship to the axis of the spindle. The location of the aperture 40 may be deliberately moved nearer one side than the other, depending on the location of a strike plate in the door frame. Regardless of the shift in position laterally, the latch housing will continue to engage the spindle housing somewhere along the length of the inwardly turned edges 51. Regardless of the location, the actuator element 48 will be in position opposite some portion of both of the semi-cylindrical parts of the spindle in which event rotation of either or both handles will successfully manipulate the latch 45.

From the foregoing description it will be clear that the parts of the cylindrical latch set herein described may be made relatively simple and need not be manufactured or machined to any considerable degree of accuracy. But relatively few sub-assemblies need be made in the factory, namely, the sub-assembly of the latch parts, the 75 sub-assembly of the spindle housing with the

spindle part on one side, and the sub-assembly of the escutcheon plate 39 with the spindle part on the other side. These parts in the hands of a carpenter or cabinet maker are readily assembled in a door wherein they can be assured of successful operation under many and varied circumstances regardless of door thickness, accidental misalignment of apertures or intentional shift of the aperture for the latch housing. Because of lack of necessity of precisely aligning the apertures, the installation work can be performed with far greater rapidity and economy than would otherwise be possible. Economy is further increased by provision of the spring pressed detent which serves the double function of assisting not only in the sub-assembly of the escutcheon plate 39 with the spindle part 16 but also the attachment of the knob 53 thereto.

While the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices.

Having described my invention, what I claim as new and desire to secure by Letters Patent is:

1. In a cylindrical latch set the combination of a spindle housing having a spindle cavity and a longitudinally extending slot communicating with said cavity, a transversely disposed latch housing having a loosely slideable engagement in said slot with the spindle housing, said latch housing having an actuator thereon, recess means on one of said housings and edge means on the other of said housings extending throughout all positions adapted to be occupied by said latch housing, said edge means loosely and slidably engaging said recess means for the adjustable retention of said housings in engaged relationship, and a spindle member having an actuator engaging face long enough to reach beneath said slot in all positions of the latch housing thereon, said spindle being mounted to extend through said spindle housing to a position disengaged from but in potential direct contact with the actuator and adapted upon rotation to engage the actuator on said latch housing.

2. A latch operating mechanism comprising a separable spindle member adapted to accommodate doors of different thicknesses, said spindle member comprising endwise extendible separate parts each having an end for attachment to a knob and a free end, said parts being adapted to be set at different positions of adjustment, an inner latch operating end on each part having a latch operating face extending from a free end thereof throughout a length in excess of the length needed to overlie the corresponding latch operating end of the other part at any selected position of adjustment, said latch operating faces being positioned adjacent each other and independently rotatable through a latch actuating movement one with respect to the other.

3. In a cylindrical latch set for a door having a transverse spindle aperture between opposite sides of the door and an intersecting edgewise extending latch housing aperture adapted to receive a latch housing the combination of a spindle housing adapted to be anchored within said spindle aperture, a separable spindle comprising

parts, each having a free end adapted to extend into the door toward the free end of the other part, each part having a latch engaging face extending from said free end inwardly and overlying the latch engaging face of the other part, one of said parts being rotatably secured within the spindle housing, the other of said parts being adapted to be positioned on the door independently of said spindle housing, said spindle housing having a longitudinal latch housing receiving slot of uniform width in a wall thereof and said slot having an open end, said spindle housing having latch housing engaging side elements at the sides of said slot extending throughout a distance corresponding to the overlying portions of said latch engaging faces.

4. In a latch spindle construction for operation with a latch bolt assembly having a semi-cylindrical spindle aperture therein, the combination of a spindle housing adapted to be anchored within the door, a separable endwise extendible spindle member adapted to accommodate doors of different thicknesses, said spindle member comprising two endwise extendible parts having free ends of each part adapted to extend toward each other when applied to the door and one of said parts being permanently attached to the spindle housing, one of said parts having a semi-cylindrical element of smaller curvature relative to the other of said parts and extending from the free end thereof substantially throughout the length of said one part and the other of said parts having a semi-cylindrical element of relatively greater curvature than said one part and extending from said free end of said other part substantially throughout the length of said other part, said parts having positions loosely overlying each other and independently rotatable one with respect to the other.

5. In a latch spindle construction the combination of a door face engaging member on each side, a separable endwise extendible spindle member adapted to accommodate doors of different thicknesses, said spindle member comprising two endwise extendible parts, each said part having one end adapted to extend through one of said door face engaging members for securing to a knob and a free end adapted to extend toward the free end of the other part, one of said parts being rotatably mounted on one of said door face engaging members, one of said parts having a latch actuating element extending inwardly from said free end, the other of said parts having a latch actuating element rotatably mounted in the other door face engaging member and extending inwardly from said free end thereof and overlying the first latch actuating element, each latch actuating element of both said parts including at least one latch actuating edge and said edges lying normally adjacent each other, said parts being independently rotatable one with respect to the other.
